DESIGN FOR A FLOOR LAMP

Hilyard R. Robinson, Washington, D. C., and
Aksel J. C. Knudstrup, Vienna, Va.

Application August 3, 1938, Serial No. 79,071

Term of patent 7 years

To all whom it may concern:

Be it known that we, Hilyard R. Robinson and Aksel J. C. Knudstrup, citizens of the United States, residing at Washington, District of Columbia, and Vienna, county of Fairfax and State of Virginia, have invented a new, original, and ornamental Design for a Floor Lamp, of which the following is a specification, reference being had to the accompanying drawing, forming a part thereof.

In the drawing:

Figure 1 is a side elevational view of a floor lamp, showing my design,

Figure 2 is a top plan of the lamp, and

Figure 3 is a vertical sectional view partly in elevation taken through the center of the upper portion of the lamp.

The dominant features of the design are shown in solid lines in the drawing.

We claim:

The ornamental design for a floor lamp, as shown and described.

HILYARD R. ROBINSON.
AKSEL J. C. KNUDSTRUP.
